UNITED STATES PATENT OFFICE.

THOMAS C. RICHARDS, OF WINSTED, CONNECTICUT.

CURTAIN-POLE.

SPECIFICATION forming part of Letters Patent No. 705,296, dated July 22, 1902.

Application filed May 17, 1901. Serial No. 60,741. (No model.)

To all whom it may concern:

Be it known that I, THOMAS C. RICHARDS, of Winsted, in the county of Litchfield and State of Connecticut, have invented certain new and

useful Improvements in Curtain-Poles; and I do hereby declare the following to be a full, clear, and exact description of the invention, such as will enable others skilled in the art to which it appertains to make and use the same.

10 My invention relates to an improvement in curtain-poles, the object of the same being to provide an ornamental device for interior decorations which can be supplied to the trade at a comparative light cost and which can be 15 adjusted to fit windows of different widths.

With these objects in view my invention consists in certain details of construction and combinations of parts, as will be more fully described, and pointed out in the claims.

20 In the accompanying drawings, Figure 1 is a view in perspective of my improved pole. Fig. 2 is a view in elevation, showing the several parts detached; and Fig. 3 is a view in transverse of the pole.

25 A represents the pole, made up of three main sections and two ornamental and detachable end trimmings. The central section A is made of thin sheet metal in the form of a tube open at its ends to receive the inner ends of 30 the wood sections B. The central section A and the outer sections B are of a general cylindrical form, each having its rear side flattened, so that when the three parts are assembled neither can rotate independently of the 35 others, thus always bringing the sides or surfaces which have been finished to form the front or exposed face of the pole in their proper relative positions. Again, in order to more closely unite the sections A and B, I 40 prefer to provide the curved faces of such sections with small corrugations, so that the ribs which are necessarily formed in corrugating the central sheet-metal section A will engage or enter the corrugations in the wooden end 45 sections, and this not only assists in preventing any independent rotation of any of the parts, but also produces sufficient frictional contact between them to prevent any accidental endwise movement. Each section is 50 provided near its outer end with a hole a, parallel with flattened face of the section for the reception of the bent ends of the screw-

bolts or hook-brackets D, which latter are held in place within the sections B by the spring-clips b.

55 E represents metal or other ornamental knobs or trimmings removably secured to the outer ends of the sections B, or, in other words, the pole is held in place so as to be prevented from vertical displacement from the hooks by 60 means of the clips b. Each clip b consists of a coiled spring, which is placed on the protruding upper end of a hook and held thereon by frictional contact, such contact being sufficient to prevent the vertical displacement 65 of the pole from the hooks.

With my improvement the pole is finished complete at the factory, with the end trimmings and screw-brackets all attached. Hence in order to place the poles in position it is 70 simply necessary to remove the screw-brackets from the pole and secure the former to the window-frame, after which the pole can be adjusted by pulling out the end sections B until the holes therein are in a position to receive the bent ends of the screw-brackets.

75 These poles can be made to fit windows of different widths within certain limits, and it will be readily seen that they not only constitute a very ornamental fixture for interior 80 decorations, but that owing to their simplicity they can be manufactured and supplied to the trade at a comparatively small cost.

Having fully described my invention, what I claim as new, and desire to secure by Letters 85 Patent, is—

1. The combination of a curtain-pole comprising three members, the central member made tubular and telescoping over the end members, and all of said members having 90 alined flattened faces, the end sections having holes through the same parallel with said flat faces, and hooks having upright members at their free ends passing through said holes.

2. The combination of a series of pole-sections, each having longitudinal corrugations, the central section made of sheet metal and telescoping over the end sections, the end sections having alining flattened peripheral faces, and the central sheet-metal section having a portion of its corrugated periphery bent and made to extend across the flat faces of 95 the end sections.

3. The combination of a series of pole-sec-

tions, the central section made of sheet metal and telescoping over the end sections, hook-brackets, each passing at one end through a hole in an end section, and spring-clips attached to said hook-brackets for retaining the pole in position relatively thereto.

In testimony whereof I have signed this

specification in the presence of two subscribing witnesses.

THOMAS C. RICHARDS.
